UNITED STATES PATENT OFFICE

2,352,665

BOX WRAPPING SYSTEM

John S. Stokes, Huntingdon Valley, Pa., assignor
to Stokes and Smith Company, Philadelphia,
Pa., a corporation of Pennsylvania

Application December 9, 1941, Serial No. 422,197

12 Claims. (Cl. 93—54.2)

My invention relates to systems for making boxes from assemblies each comprising a box blank, or equivalent, manually registered by an operator at an assembly station upon an adhesively-coated wrapper, label or equivalent, generically termed a "wrapper."

A major object of my invention is the provision of systems for and methods of producing assemblies of box structures or unstayed box blanks with wrappers so constituted and characterized that the order of magnitude of loss of time, in terms of loss of production of wrapped boxes per week or other suitable unit of time, for changing over from production of assemblies for boxes of one size to production of assemblies for boxes of another size, is much less than the order of magnitude of loss of time occurring in so changing over fully automatic systems.

My invention resides in semi-automatic systems for, and methods of, assembling box structures, especially unstayed box blanks, with wrappers, more particularly wrappers provided with tabs or the like for staying unstayed box blanks, characterized by operating coordination with each other by an operator of units which respectively automatically deliver box structures or blanks and wrappers, within reach of the operator who then registers or assembles the box structures or blanks with or upon the wrappers; and more particularly my said systems and methods may comprise, further, a wrapping unit for or a wrapping step of automatically converting the assemblies into wrapped boxes, the assemblies being either automatically or by intervention of a second operator transferred or delivered to the wrapping unit.

In accordance with my invention, the box blanks are fed toward the operator and delivered in turn at a predetermined position within reach of the operator and in predetermined orientation or position with respect to the orientation or position of the wrapper with which it is to be manually assembled; more particularly, the wrappers are fed intermittently or step-by-step toward the operator, and each in turn comes to rest near her in a predetermined position, in substantial alignment with, and in predetermined orientation or position with respect to an individual box blank which has been fed toward the operator and has come to rest near her in another predetermined position.

Further in accordance with my invention, members for controlling the feeding and coating of the wrappers, the feeding and delivery of the box blanks (which may be pre-bent either before

or during feeding and delivery thereof), and conversion of the assemblies into wrapped boxes are all located at the assembly station for actuation there by the operator for supervision of the operation of the system as a whole and for intervention at any time in the control or to initiate operation of any one or more significant mechanisms thereof.

My invention further resides in the methods 10 and in the systems having the features herein-after described and claimed.

This application is in part a continuation of application Serial No. 338,694, filed June 4, 1940, Patent No. 2,295,461, September 8, 1942.

15 For an understanding of my invention and for illustration of various systems embodying it, reference is made to the accompanying drawings in which:

Fig. 1 is a front elevational view of mechanisms 20 comprising a semi-automatic box wrapping system;

Fig. 2 is a plan view of the arrangement shown in Fig. 1;

Fig. 3, in perspective, discloses the arrangement 25 by which an operator may control or supervise the operation of the component mechanisms of the Figs. 1 and 2;

Fig. 4 is a side elevational view of blank-bending and feeding mechanism as shown in Figs. 30 1 and 2;

Fig. 5 is a detail view, on enlarged scale and with parts broken away, showing significant elements of the mechanism of Fig. 4;

Fig. 6, in perspective, shows a box blank after 35 operation thereon of mechanism shown in Fig. 5;

Fig. 7 is a front elevational view of mechanisms comprising another semi-automatic box wrapping system.

Fig. 8 is a plan view of the system of Fig. 7;

40 Fig. 9, in perspective, illustrates the elements significant in control by the operator of the various mechanisms shown in Figs. 7 and 8;

Fig. 10 is a fragmentary view, in plan, illustrating a modification of the wrapper-conveying 45 mechanism of Figs. 7-9;

Fig. 11 is a side elevational view of parts appearing in Fig. 10;

Fig. 12 is a side elevational view of another semi-automatic system embodying my invention;

50 Fig. 13 is a plan view of the system of Fig. 12;

Fig. 14, in perspective, discloses an arrangement for control by the operator of the mechanisms shown in Figs. 12 and 13;

Fig. 15 is a plan view illustrating a modification 55 or rearrangement of Fig. 13;

Fig. 16 is a side elevational view of another semi-automatic box wrapping system; and

Fig. 17 is a plan view of the component mechanisms thereof;

Fig. 18, in perspective, illustrates an arrangement for control by the operator of the mechanisms shown in Figs. 16, 17, 19 and 20;

Fig. 19 is a side elevational view of another semi-automatic system embodying my invention; and

Fig. 20 is a plan view thereof.

Referring to the system shown in Figs. 1 and 2, in each cycle of the mechanism G, preferably of type disclosed in Bailey application Serial No. 334,149 filed May 9, 1940, Patent No. 2,276,683, March 17, 1942, and Federwitz et al. application Serial No. 397,894 filed June 13, 1941, a wrapper or sheet W is lifted by the suction gripper 1 from the top of the stack S and delivered to rolls 2, 3 which feed it to adhesive-applying roll 4; the adhesive coated wrappers are each in turn deflected by stripper blades 5 from roll 4 onto conveyor belt 6 which is driven intermittently or step-by-step by mechanism G to advance the wrappers toward an operator located at the assembly station 0 indicated by stool or chair 7.

Suction is applied through the conveyor belt to hold the freshly coated wrappers flat during their transport and during register thereon, by the operator, of box blanks.

To each of the wrappers there may be applied, preferably in accordance with aforesaid application 397,894 or with United States Letters Patent 1,857,260 to Rider, a group of tabs t cut from the rolls R of tabbing material.

The lever 8, disposed adjacent the assembly station 0, is provided to allow the operator from that location to actuate the bleeder valve 9A of the gluer mechanism G when she desires to prevent the gripper 1 from removing a wrapper from the stack S without interruption of feed of wrappers already on conveyor belt 6. When mechanism G is of the aforesaid preferred type, the interruption of suction automatically prevents supply to belt 6 of tabs which otherwise would be coated with adhesive and delivered thereto, without wrappers.

For each cycle of operation of mechanism B, a prescored, corner-cut box blank BB is removed from stack BS thereof and delivered into the path of a plunger 9 which carries the blank downwardly adjacent two sets of bending tools which sharply bend the sides and ends of the blank along the scoring so there to weaken or fracture the fibres of the blank material that tendency of sides and ends of the completed box to bow is substantially overcome. The bent blank upon its release from the plunger 9 is received by conveyor 10 which transports it to a position, accessible to the operator at station 0, determined by the stop 11, Fig. 4.

The blank-bending and delivering mechanism B is so disposed with respect to the conveyor 6 that each blank, as positioned by stop 11, is in substantial alignment with a wrapper W at rest, in front of the operator, upon the step-by-step conveyor 6. As hereinafter appears in discussion of Fig. 3, the timing of operation of the conveyor 6 with respect to the sheet-removing mechanism may be varied so that whatever may be the size of the selected wrappers, the center line of each in direction of movement of conveyor 6 will be in alignment with the center line

of form block 12 of the wrapper-applying mechanism M when, at the end of one of the steps of conveyor 6, the wrapper arrives at the transfer or delivery station. The orientation of the bent blank as delivered in front of the operator by conveyor 10 is predetermined with respect to the orientation of at least that wrapper upon conveyor 6 with which it is to be registered by the operator; the orientation is such that the short sides or ends of a box blank on stop plate 11 are substantially parallel with the end-covering flaps of the wrapper at the assembly station and the long sides of the box blank are substantially parallel with the corresponding long flaps of the wrapper.

The mechanisms G and B are so timed that for each wrapper W delivered by conveyor 6 in front of the operator, a bent box blank is delivered by conveyor 10 to position in front of and accessible to the operator. In consequence, the operator upon arrival of each successive wrapper at the assembly station need merely remove or lift an individual bent box blank, having proper orientation, from the position defined by stop 11 and move it forwardly and downwardly into registered adhesive engagement with the wrapper at rest at the assembly station to form an assembly A.

The assemblies A so manually produced are advanced step-by-step by conveyor 6 toward the wrapping mechanism M, preferably of the type disclosed in United States Letters Patent 2,119,980 and in co-pending Bailey application Serial No. 314,375 filed January 13, 1940, Patent No. 2,262,788, November 18, 1941, so disposed with respect to conveyor 6 that, as above stated, a box and wrapper assembly is positioned, at the completion of one of the stepping movements of conveyor 6, in substantial alignment with the form block 12 of the wrapping machine M.

Once for each cycle of mechanism M the grippers 13 of the transfer mechanism T, a component of mechanism M, erects the side and end walls of the box blank at the delivery end of the conveyor 6 and transports the assembly A comprising that blank and the wrapper attached thereto into the path of form block 12 which during its descent moves the assembly adjacent the path of movement of various tools which apply the side panels of the wrapper to the erected side walls of the box. In the next cycle of the mechanism M, the carriage 14 transfers aforesaid box and wrapper assembly into the path of a second plunger 15 which during its descent moves the partially completed assembly adjacent another group of sheet-applying tools for application of the end panels to the box and turn-in of the marginal portions of all wrapping panels, all as more fully described in United States Letters Patent 2,119,980 to Bailey.

Concurrently with transfer of a partially completed assembly from below plunger 12 toward the path of movement of plunger 15, carriage 14 pushes a completely wrapped box from the machine or onto the guides 16, 16.

So long as a supply of wrappers and box blanks is maintained in the wrapper coating mechanism G and the blank bending mechanism B, the sheet applying mechanism M is permitted automatically to control the timing of mechanisms B and G, but there are provided, at locations convenient to the operator at the assembly station 0, various controls, Fig. 3, by which the operator

may independently control the operation of the mechanisms B, G and M. For example at the beginning of a run or after a prolonged interruption, the operator by depressing control treadle 35 can effect operation of the wrapper feeding mechanism G alone and then when sufficient wrappers have been delivered to conveyor 6 to bring the first of them at the assembly station, initiate operation of the blank bending device B by pulling out knob 76 so to provide for supply of blanks which she may register upon the wrappers. When the first of these assemblies reaches the transfer station, the operator by depressing control treadle 102 may then initiate operation of the wrapping machine M for transfer of the assemblies in turn to form block 12. Knob 76 and treadle 35 are then permitted to return to their original positions and so long as treadle 102 is held depressed the mechanism M will repeat its cycle and in each cycle initiate, through cams 38, 71, a cycle of each of the mechanisms G and B.

If during a run, the operator serving also as inspector, notices upon the conveyor a wrapper which for one reason or other is unsuitable, or notices absence of a wrapper, she may lift pedal 102 and so interrupt operation of mechanism M with the result mechanisms B and G also stop upon completion of their cycles already initiated. Furthermore when a run is to be completed, when the supply of wrappers is depleted, or the system is to be shut down at the end of a working period, the operator by actuation of handle 8 interrupts operation of the wrapper feeding mechanism I (and of the tab feeding mechanism as well) but allows continued operation of conveyor 6 and of mechanism M so to clear the conveyor 6 of, and to make boxes from, assemblies which she has already formed.

After the last assembly has been made, the operator interrupts supply of box blanks to the assembly station by opening switch 64S in the circuit of the motor 64; conveyor 6 continues to operate until after delivery of the last assembly to the wrapping machine M.

An arrangement providing such control of mechanisms G, B, M by the operator at the assembly station is shown in Fig. 3. The motor 17, Fig. 1, through belt 18, pulley 19 and gears 20, 21, 22, Fig. 3, continuously drives worm wheel 23 which also serves as the driving element of a clutch. To the shaft 24 of mechanism G is keyed or otherwise suitably secured the driven element 25 of the clutch; pawl or dog 26 carried by member 25 is biased by spring 27 into driving engagement with the continuously rotating clutch element 23. When mechanism G is idle the pawl 26 is held from engagement with the rotating clutch member 23 by the latch 28 supported for movement into and out of the path of pawl 26 by stationary guide 29. The operating linkage for the latch 28 includes the arms 30 and 31 attached to shaft 32, the link or bar 33 which is connected at the assembly station to one arm 34 of aforesaid treadle member 35 and at its remote end to one arm of lever 36, actuatable by cam 38 on shaft 39 of the sheet applying mechanism M.

When latch 28 is withdrawn from the position shown in Fig. 3, either intermittently by cam 38 once per cycle of the sheet applying mechanism M or by the operator who momentarily depresses or holds depressed, treadle 35, the spring 27 effects engagement of the clutch members 23, 26 so to initiate a cycle of the sheet-coating mecha-

nism, completed in a period somewhat shorter than the period corresponding with a cycle of the sheet applying mechanism M. When the operator releases the treadle 35 or when cam 38 of the wrapping machine permits, the latch 28 under control of biasing spring 40, for example, is returned into the path of the dog 26; therefore at the end of the cycle, the latch 28 rocks dog 26 out of engagement with the continuously rotating clutch member 23 and stops the machine G.

During the cycle of mechanism G, the cam 41 effects actuation of the conveyor clutch comprising driving member 43 and driven member 44 interposed between the driving rolls 45 of the conveyor belt 6 and the continuously rotating gear 46 attached to or integral with the driving clutch member 43. The driven clutch member 44 is slidably keyed to shaft 47 to which the lower feed roll 45 is secured and is provided with a groove 48 which receives the thrust members 49 supported by the upper forked end of lever 50 provided at its lower end with a cam follower 51 received by the cam groove 52 of cam 41.

Suitably after beginning of a cycle of mechanism G, one revolution of shaft 24, the rise 53 of cam 41 effects clockwise movement of arm 50 so to effect engagement of the clutch members 43 and 44. The conveyor belt 6 thereupon moves, for about a half cycle of mechanism G, to advance the wrappers towards the operator until the rise 54 of cam 41 causes separation of the clutch members 43, 44.

The angular distance between the rises 53, 54 of cam 41 is fixed and consequently the steps of the conveyor are all of the same length. To ensure that at the end of a step of conveyor 6 there shall be at the assembly station 0 and at the transfer station T a wrapper, which, regardless of its size, shall be centered or in alignment with the form blocks 9 and 12 respectively, the clamping nut 42 is loosened and the cam 41 adjusted angularly with respect to shaft 24 to obtain the proper timing between the operation of the conveyor and the operation of the sheet removing and feeding mechanism including the suction gripper 1. At fixed time in each cycle gripper 1 moves toward and from the top sheet of the stack; suction is applied through gripper 1 under control of the reciprocating member 55 which actuates the bleeder valve 56 in the suction line 57 from pump P to the suction gripper 1.

When the operator desires continued step-by-step movement of the conveyor for transport of wrappers or assemblies thereon without feed of additional wrappers thereto, she interrupts supply of suction to the gripper 1 by changing the position of valve 9A in the suction supply line 57. Valve member 9A, as above stated, is connected to the control lever 8 at the assembly station; the linkage between these members, Fig. 3, includes the rods 58 and 59 interconnected by the bell crank lever 60. The members 61 and 62 for pivotally supporting the control lever 8 and bell crank 60 may conveniently be mounted upon one of the side members of the suction housing 63 for the conveyor belt 6.

In resumé, the control members 8 and 35 permit the operator at the assembly station 0 at any time to initiate a cycle of mechanism G independently of mechanisms M and B and to interrupt the supply of wrappers and tabs to conveyor 6 without interrupting operation of any of the other mechanisms.

The motor 64 drives the blank-bending mech-

anism B through belt 65 and pulley 66, which serves as the driving element of a clutch whose driven member is attached to shaft 68 and biased as by spring 67 toward member 66 but is restrained by means including forked member 69, the notched member 70 attached thereto, and the latch member 71. The lever 72 to which latch 71 is pivotally connected is in turn connected by rod 73 and bell crank lever 74 to rod 75 which extends to position accessible to the operator at the assembly station and is there provided with the control knob or member 76. In the particular arrangement shown, when the operator pulls the knob 76 toward her the latch 71 is pulled downwardly out of the notch in member 70 whereupon the spring 67 is free to effect engagement of the clutch members and so initiate a cycle of the bending mechanism B independently of operation of the wrapper-applying mechanism M.

With control knob 76 in its inner position and with control pedal 102 held depressed by the operator, withdrawal of the latch member 71 is intermittently effected automatically under control of cam 77 on shaft 39 of the sheet applying mechanism M by means including the supporting lever 78 for the cam follower 79 and linkage between the levers 72 and 78 including the rod 80, 81, 82 and the bell crank levers 83, 84.

The mechanism for re-setting latch 71 and interrupting operation of mechanism B at the end of a cycle thereof, completed in shorter time than a cycle of mechanism M, comprises a cam 85 which makes one revolution per cycle of mechanism B. The lever 86 carrying the cam follower 81, biased for continuous engagement with cam 85, is connected as by link 88A to the reciprocable guide block 88 of the latch 71. During a cycle of mechanism B, the guide block 88 is moved by cam 85 to bring the latch 71 into alignment with the notch in member 70 so that the latch 71 when released may enter the notch. Near the end of the cycle, the cam 85 returns the guide 88, latch 71 and member 70 to the position shown in Fig. 3 and so effects disengagement, in opposition to spring 67, of the clutch interposed between motor 64 and the blank bending mechanism.

The driving motor 89 of the sheet wrapping mechanism M effects through belt 90 and pulley 91 continuous rotation of the driving member of a clutch similar to that above described in connection with the bending mechanism B. More particularly, the driven member 93 of the clutch attached to shaft 92 of the machine is biased by spring 94A toward engagement with the driving member of the clutch. The clutch members are held separated in opposition to spring 94A by means including the yoke member 94, the notched member 95 attached thereto and the latch 96 slidable through the reciprocable guide 97 and having a pin and slot connection with the bell crank lever 98 suitably connected as by rod 99, lever 100 and shaft 101 to the control treadle 102 at the assembly station 0.

When latch 96 is released by depression of treadle 102 the spring 94A effects engagement of the clutch members and the motor 89 thereupon through shaft 93 and parts driven thereby effects movement of the plungers 12, 15, carriage 14, and the associated sheet applying tools. Reengagement of the latch 96 and notched member 95 and their movement while so engaged to separate the clutch members is effected by cam 85A connected to guide 97 by bell crank lever 86A and link 87A.

During each cycle of mechanism M, cams 38

and 77 attached to shaft 39, connected as by gears 103-111 to shaft 93 make one revolution and through their actuation of the latches 28 and 71 of sheet-coating mechanism G and blank-bending mechanism B provide for delivery to the operator at the assembly station 0 of another box blank and another wrapper.

The disposition at the assembly station of the control members 8, 76, 35 and 102 and "start" and "stop" switch 64S permits the operator there to initiate and interrupt the operation of the system as a whole and independently to control the supply of wrappers and tabs to the conveyor belt, the delivery of box blanks and wrappers to the assembly station, and formation of wrapped boxes from the assemblies of box blanks and wrappers. The centralization of the controls at the assembly station permits the operator from that location to cope with any contingency that may arise and to effect the proper sequence of initiation and cessation of operation of the mechanisms G, B and M, or components thereof, at the beginning and end of a period of normal operation of the system as a whole.

Efficient and skilled operators working under favorable box factory conditions, such as use of highest qualities of box-blanks, wrappers, tab material and adhesives, and provision of expert maintenance of the machines, may run the system without interruption and for long periods, by keeping depressed the control member 102, Fig. 3.

Operators of lesser ability or experience, and more especially if factory conditions are adverse, frequently need to start and stop conveyors 6 and 10 either simultaneously or individually, and may selectively operate any of the control members 64S, 76, 102 and 35, Fig. 3, to meet the various situations arising.

Previously in so-called semi-automatic systems in which an operator registered box blanks on wrappers, unstayed box blanks were commonly stacked on a table or support disposed to one side of the operator who, in each interval between successive steps of the conveyor which transported the wrappers, was compelled to concentrate and direct her attention and efforts upon removal of only the top blank of the stack, and then redirected her attention and efforts to the wrappers on the conveyor before attempting to register the blank upon a wrapper to form an assembly. The difficulty of removing blanks, particularly corner-notched blanks, one at a time, without upsetting or disarranging the stack thereof, forced the operator relatively slowly or carefully to perform the act of blank-separation with consequent need for haste in the essential assembling step which requires appreciable time for accurate registration of the box blank upon a wrapper.

In the systems of Figs. 1 and 2 the delivery of box blanks individually in succession, one for each wrapper delivered to the assembly station, to a predetermined position and definite orientation with respect to its assigned wrapper adjacent the assembly station and there free, displaced from the blank next to follow, for instant manual removal without regard for or effect by the succeeding blank or blanks, relieves the operator of the distracting tension, hesitation and fatigue incident to separating each blank from an unstable stack thereof with the results neater boxes and substantially greater number of boxes are produced per working day or week, all with less demand upon the nervous energy of the operator.

When this semi-automatic system is used for

short runs for production of wrapped boxes of different sizes, the output, averaged over a working week, for example, compares favorably with, and in cases exceeds, the output actually achieved, under the same conditions, by the so-called full-automatic systems, exemplified by United States Letters Patent 1,831,236 and 2,111,700, in which all operations including assembly of box blanks or boxes with wrappers are automatically performed.

For short runs with different sizes of box blanks, the necessary practice of nearly all box-making plants, the loss of time required to re-set the full-automatic machines, such as above mentioned, particularly the blank and wrapper assembling mechanism thereof, more than offsets the difference between its output, in boxes per minute of actual operation, and the output of my semi-automatic systems exemplified by Figs. 1 and 2 and the herein disclosed variants.

By way of example, when four or five different sizes of boxes are made in the course of a week, with the full-automatic system such as above mentioned, the hours of box production lost, in or due to re-setting and/or substitution of various parts to accommodate the different sizes of boxes, is approximately three times as great as with any of the semi-automatic systems herein disclosed. Under the same circumstances, with the full-automatic system, the loss of production of boxes due to time required for change-overs (aforesaid resetting and/or substitution) is at a rate of the order of 15,000 boxes per week, whereas the loss of production for the same cause with the semi-automatic system, exemplified by Figs. 1 and 2, is at a rate of the order of only 5,000 boxes per week, and with other semi-automatic systems hereinafter described is at a rate of the order of only 2,000 boxes per week.

In any of the systems of the character herein-described, the blank bending mechanism B may be the general equivalent thereof or of the type disclosed and claimed aforesaid Federwitz Patent No. 2,295,461, or preferably may be of the type disclosed in Figs. 4 and 5 hereof.

The mechanism for feeding the blanks one at a time, from the top of stack BS to the predetermined position and orientation from which manually removed, includes the slide 112, Fig. 4, upon which is pivotally supported the blank pushing member 113 biased to engage the top of stack BS, as by spring 114. The slide 112 is reciprocated from and back to the position shown in Fig. 4 by mechanism including the cam 115, which makes one revolution for each cycle of mechanism B, and arms 116 and 117 attached to shaft 118; the former supports a cam follower continuously in engagement with cam 115 and the latter is connected, as by rod 119 to lever 120 attached to shaft 121 to which is suitably secured arm 122 connected by link 123 to arm 124 attached to shaft 125 to which is also attached arm 126 connected by link 127 to slide 112.

As slide 112 is moved to the right, Fig. 4, the top blank is moved by the pusher element 113 to bring the forward end of the blank between and into engagement with the continuously rotating feed rolls 128. To ensure separation of only a single sheet there is provided at the forward end of the stack the roll or bar 129, Fig. 5, which bears upon the upper face of the top sheet of the stack near its forward edge, and the bar 130A which engages the front edge of the stack and so spaced vertically from the bar or roll 129 there is

defined an aperture of width sufficient to pass only a single box blank.

The momentum of the blank as it leaves the feed rolls 128 is sufficient to position it on the 5 guide plates or rails 130 beyond the registering member 131, Fig. 5, pivotally mounted at its upper end upon the forward end of the slide 132. Upon return of the slide 132 to its retracted position, Fig. 5, the stop bar or pin 133 engages the registering member 131 to swing it upwardly about its 10 pivot 134 to position sufficiently above the surface of plate 130 to allow unobstructed passage of a blank emerging from the feed rolls 128. The operation of the slide 132 is so timed that after a blank has been fed onto spaced plates 130, the 15 slide 132 is moved to the right whereupon the registering member, by swinging clockwise about pivot 134, moves into contact with, or closely adjacent, the upper surface of plate 130 so that as the slide continues to move to the right member 131 engages the rear edge of the blank and moves it into engagement with stops 135 so positioned that when the blank is engaged thereby the score lines Y, Y are in register with the corresponding edges of the form 9. The plates 130 20 are so spaced their adjacent edges are in register with the score lines X, X of the blank.

The rack 136, Fig. 5, attached to or integral 25 with the slide 132 is continuously in mesh with gear 137 on shaft 138, Fig. 4, to which is attached, externally of one of the side frames of the machine, a gear 139 continuously in mesh with rack 140 secured to the upper end of rod or bar 141. The threaded rod 142 supported by arm 143 and 30 threadably engaging block 144 pivotally secured to the lower end of arm 141 provides for adjustment of the stroke of slide 132 so to accommodate the registering mechanism to blanks of different sizes. Arm 143 is attached to shaft 144 to which 35 is also attached the arm 145 provided with a cam follower for a cam rotatable with shaft 116 which makes one revolution per cycle of the blank bending mechanism B.

The reciprocation of the form-block 9 is controlled by a cam not shown operatively connected 40 thereto by linkage terminating in arm 147 and connected as by link 148 to the pin 149 extending from plunger 150 to the lower end of which is suitably secured form-block 9.

50 The bending of the blank during its descent with plunger 9 is effected by two pairs of reciprocating tools; one pair 151, 151A is shown in Fig. 5; the other pair, 152, 152A, are at right angles thereto. In construction all four tools 55 are similar.

Tool 151, for example, comprises a lower member 154 which for part of its movement engages the lower face of the bottom panel of the box blank and an upper bending or pinching member 60 155 whose box engaging face is inclined downwardly and outwardly forming with the lower member 154 a narrow slot. As the tool 151 moves inwardly to position corresponding with that of tool 151A, Fig. 5, a side panel SP of the box blank is sharply bent with respect to the bottom.

The tool support 151 is adjustably secured by bolt 156 to the reciprocable member 157 connected by link 158 to crank arm 159 which for 65 each cycle of the machine swings from and back to a position for which the lower member 154 of the bending tool is out of the path of movement of the plunger 9. The oscillation of the arm 159 is effected by the cam 169 which during each revolution of shaft 169A, corresponding 70 with a cycle of the mechanism, causes the shaft 75

170 to oscillate from and back to aforesaid position; the motion of shaft 170 is transmitted to lever 159 by the link 171.

By generally like mechanism each of the other bending tools is moved, during a cycle of mechanism B, from and back to retracted position clear of the path of the form block to bend a corresponding side or end panel of a box blank. The side and end panels of the bent blank, as permitted upon retraction of the lower bending tools to fall onto conveyor 10, remain in substantially upright position, Fig. 6.

The side and end panels of the blank after movement of the plunger beyond the plates 130 are restrained in partially erected position by the two pairs of guide plates 172, 173 individually supported by and depending from the slides 174, 175 each adjustable, for accommodation of box blanks of different widths, toward and from the path of form block 9. This adjustment of each slide is effected by a crank 175A connected by shaft 176 and gears 177, 178 to shaft 179 which threadably engages the slide. The plunger 9 moves downwardly from and upwardly to its upper position, Fig. 5, without pause or dwell; the form is apertured to prevent movement of the blank upwardly with the form.

As the stack BS of blanks is depleted, a level-measuring arrangement, not shown, controls upward feed of the stack by a pair of chains 180, one on either side of the stack, and each connected to a stack-supporting ledge 181 guided by a pair of bars 182. When one stack is depleted, the support 183 therefore which bridges the gap between the two ledge members 181 is removed and the ledge or carriage members dropped to their lowermost position to receive another stack BS and its support 183.

The conveyor 10 for transporting the bent blanks to position accessible to an operator at the assembly station may operate continuously or preferably it is advanced step-by-step for successive cycles of the machine; in Fig. 5, the drive roll 184 of conveyor 10 is shown connected by means including a chain or belt 185 to shaft 186 connected by pulley 181 and chain or belt 188 to shaft 189 which rotates once per cycle of mechanism B.

As above stated a cycle of the mechanism B may be initiated either manually by actuation of knob 76 or automatically by cam 77 of the wrapping machine M. Mechanism B may be also tripped by handle 191 or equivalent member connected to the control linkage, for example, rod 80, when for any reason it is desired, as during setting-up of the machine, to do so.

In that modification of my system shown in Figs. 7-9, the blank-bending mechanism B may be of the same type disclosed in, or mentioned in connection with, Figs. 1-3 and the mechanism G1, except in respect hereafter specifically mentioned, may be similar to the mechanism G of Figs. 1-3. In general those elements in Figs. 7-9, and of the remaining figures, having the purpose and function of elements of Figs. 1-3 are identified by the same reference characters.

The sheet applying mechanism M1 is generally of the type disclosed in Letters Patent 2,115,539 or in Letters Patent 2,094,455 of which it is characteristic that the operator moves the assemblies A in turn onto the form block 12A of the wrapping machine and momentarily holds each of them until the clamping members 191 or equivalent relieve her of that task. The wrapped

boxes are removed from the machine by the plunger 199 which pushes them in turn onto the chute 200.

As in the system of Figs. 1-3, wrappers W are fed step-by-step by conveyor 6 from the adhesive-coating mechanism to position in front of an operator at the assembly station 0 and to this same station there are fed box blanks, one for each wrapper, with delivery thereof in predetermined orientation with respect to the orientation of the wrappers. The operator to form an assembly A need merely pull a box blank BB from plate 11 (Fig. 4) and then move it downwardly and forwardly into registry with a wrapper on conveyor 6 (Figs. 6, 7). Plate 11 if narrower than the widest blank may have an upturned lip to serve as a stop; otherwise a lip is unnecessary though preferably the plate should be faced with a material such as sandpaper, felt, or the like having suitably high coefficient of friction.

The conveyors are so timed that the operator 0 with box blank in hand need only wait for conveyor 6 to come to rest and at once register on a stationary wrapper and in a period sufficiently long that the blank may be carefully registered without fear the conveyor 6 will restart before the registration is completed.

The assemblies A so formed are advanced step-by-step beyond the assembly station 0 for delivery to another operator at the transfer station TS at which the stool or chair 192 is disposed. This operator may either permit the assemblies to discharge from conveyor 6 onto the table 193 from which she may lift one at a time onto the form block 12A, or she may prefer to transfer the assemblies directly from the conveyor belt to the form-block.

The operator at the assembly station 0, as in Figs. 1-3, may manually control the operation of mechanisms B and G1 independently of operation of mechanism M1 and may for normal operation of the system allow automatic control of the mechanisms B and G1 by the sheet-applying mechanism M1. More particularly, the operator at assembly station 0 may control the feed of box-blanks to her by changing the position of control knob 76 conveniently located for her actuation without movement from the chair 1. From that same position the operator, by actuation of the handle 8, may interrupt the supply of wrappers W and tabs to conveyor belt 6 yet provide for continued step-by-step movement of the conveyor belt to clear it of previously formed assemblies. Also from that location, the operator by depressing the treadle 35 may initiate a cycle of the sheet-coating mechanism G1 independently of the operation of the box-wrapping mechanism M1 or of the blank-bending mechanism B. From that same location, the operator may, by depressing and releasing the treadle 102, control the operation of the box-wrapping mechanism M1.

If desired, all of these controls may be subject to sole supervision by the operator at the assembly station 0, leaving the operator at the transfer station TS free to devote her attention wholly to the task of transferring the assemblies A to the form block 12A of the wrapping machine M1. However, by duplication of some or all of these controls at the transfer station TS the operator there may, if necessary, replace or supplement the supervision of the operator at the assembly station. For example, the rod 58 for connecting control handle 8 of the suction valve

9A may be extended (as in Fig. 12) to the wrapping machine M1, Figs. 7 and 9, and there connected to handle 8A accessible to the operator at the assembly-transfer station; the rod 33 may be connected to treadle 35A disposed in position convenient for actuation of the operator at the transfer station so to permit her, in supplement or replacement of the operator at the assembly station, to control operation of the sheet-coating mechanism G1 independently of the box-wrapping mechanism M1; to shaft 101 may be attached treadle 102A in position convenient for operation by the operator at the transfer station that she may therefore, in replacement of or in supplement to the operator at the assembly station, control the operation of the box-wrapping mechanism M1.

In substitution for the foot treadle 102A, or in addition thereto, there may be provided the lever 194 terminating in control handle 195 which can be grasped by the hand of the operator at station TS for effecting engagement or disengagement of clutch members interposed between the driving motor 89 and the main shaft 39 of the wrapping machine M1.

Referring to Fig. 9 for discussion of those other particulars in which the arrangement of Figs. 7, 8 differs from that of Figs. 1-3, the mechanism for controlling the separation of the clutch members 43, 44 interposed between motor 17 and the conveyor drive rolls 45 comprises two relatively adjustable cam members 196, 197; the former is secured to shaft 24 in fixed angular relation with respect thereto and the latter, clamped as by hand nut 198 to member 196 is slotted to permit adjustment to different angular positions with respect to shaft 24. The rise 53 of cam 196 having fixed angular relation with respect to shaft 2, the clutch members 43 engage at the same point in succeeding cycles and consequently conveyor belt 6 starts to move at the same point in succeeding cycles of mechanism G1. The rise 54 of cam 197 engages the lever 50 to effect separation of the clutch members at a time in the cycle dependent upon the selected setting of disk 197. Therefore the extent to which the conveyor belt 6 advances the wrappers in each step may be varied, not possible with the arrangement shown in Fig. 3; accordingly a larger number of wrappers or assemblies may be accommodated at one time by the conveyor belt 6 when small boxes are to be made and wrapped. The length of the step is preferably so selected however that at the end of each step a wrapper is disposed at the assembly station 0 in position convenient for the operator there to move into engagement therewith a box blank positioned on plate 11; this selection may be without meticulous regard for the position, at the end of a step, of an assembly A at the discharge end of the conveyor 6.

In the adhesive-applying mechanism G1, Fig. 9, the mechanism for controlling engagement and disengagement of the clutch members 23, 26 is somewhat different from that disclosed for the adhesive-applying mechanism G of Figs. 1-3. More particularly the latch 28 is supported in a stationary guide 30A and is provided with a pin 202 received by a slot in the lever 30A connected to rod 33 for actuation by the pedals 35, 35A. When either pedal is depressed the arm 30A is swung counter-clockwise to withdraw the latch 28 from engagement with the clutch dog 26; when the pedal is released the spring 203 returns the latch 28 and arm 30A to the position

shown in Fig. 9 for re-engagement with dog 26 at the end of a cycle to effect disengagement of the clutch members.

In wrapping machine M1, Fig. 9, the arrangement for controlling engagement and disengagement of the clutch between the driving motor 89 and the main shaft of the machine is somewhat different from that utilized for like purpose in the wrapping machine M of Figs. 1-3. More particularly, when treadle 102 or 102A is depressed, the arm 204 is swung in clockwise direction to withdraw the latch member 205, against a biasing spring, not shown, from engagement with the cam 206 rotatable with the main shaft 39 of the wrapping machine, or with any other shaft thereof making one revolution per cycle. The withdrawal of the latch member 205 permits lever 208 to rise and thus permit the spring 207 to move the clutch members into engagement with one another. Assuming the treadle has been released to allow the latch member 205 to move into the path of cam 206, the latter near the end of the cycle of the machine engages and depresses the latch member 205 so separating the clutch members through the linkage comprising the bell crank lever 208 which supports the latch 205, the bar 209, and the forked clutch member 210.

In modification of the arrangement shown in Figs. 7, 8, the single conveyor belt 6 may be replaced by longer belt 6A, Figs. 10, 11, extending between the operator TS and the path of the form block 12A of the wrapping machine and sufficiently narrow to allow the operator to reach over the conveyor to the form block 12A for disposition thereon of the assemblies A removed in turn from position directly in front of her on belt 6A. To accommodate large as well as small wrappers, there is provided on either side of belt 6A a narrow belt or equivalent 6B operated in unison with belt 6A and increasing the effective width thereof but only to position short of the operator at the transfer station. Features of this modification are described and claimed in co-pending application Serial No. 442,919 filed May 14, 1942.

In the modification of my system shown in Figs. 12-14, the wrapping machine M1 is of the same type used in the system of Figs. 7-9, the blank bending mechanism V is of the type used in systems of Figs. 1-3 and 7-9, and the adhesive-applying mechanism G is of the type shown in Figs. 1-3. With this explanation, there is no need specifically to discuss the construction or operation of the mechanisms M1, B, and G of Figs. 12-14.

The conveyor 6A for transporting coated wrappers from the mechanism G passes in front of both operators, one seated on chair 1, at the assembly station 0, directly opposite the bending mechanism B, and the other seated on chair 192, at the transfer station TS, directly opposite the wrapper-applying mechanism M1. In each cycle of the system, the conveyor 6A comes to rest with a coated wrapper W in front of the operator at the assembly station, and the blank bending mechanism by conveyor 10 delivers an individual bent box blank directly in front of her; the operator need merely transfer the blanks in succession from rest on conveyor 10 onto the wrappers as each in turn is delivered in front of her. There is ample time to effect this act of registration even when the system is operated at high speed.

In each cycle of the system, the operator at

the transfer station TS need merely lift an assembly A from the conveyor 6A directly in front of her and hold it momentarily against the form block 12A. There is ample time in the cycle of the system for the second operator to perform this simple act even when the rate of production of boxes is high, for example, at the rate of approximately forty boxes per minute.

In the arrangement shown in Figs. 12 and 14 the operator at station TS may, by means of treadle 102A or handle 195, start and stop the wrapping machine M1; she may by actuation of the control handle 8A interrupt the supply of wrappers and tabs to the conveyor 6A; and by actuation of treadle 35A may control the coating mechanism G.

The operator at the assembly station 0 may, alternatively to the operator at the transfer station, control the operation of the wrapping machine M1 and may alone or with the operator at the transfer station control, by handle 8, the delivery of wrappers and tabs to the conveyor 6A. She may also manually control the operation of the adhesive-applying mechanism G by pedal 35 conveniently located adjacent chair 7. This control may be in substitution for or in replacement of the control available to the operator at the transfer station and there afforded by the pedal 35A, Fig. 14. Normally, the more capable of the two operators may run the system without interruption and for long periods, from either station TS or station 0, by keeping depressed the control member 35A or 35, Fig. 14, respectively.

However, when there occur irregularities in the box blanks or tabbed wrappers, or mishances in the delivery of the box blanks or wrappers, both operators simultaneously or either operator individually by selection may operate suitable one or ones of the control members 35A, 102A, 102, 35, 16, 64S and 195 to start or stop automatic mechanisms G and B, or either of them.

The system shown in Fig. 15, includes the same units as in Figs. 12 to 14, but for access to the wrapper-applying mechanism M1 and to the blank bending mechanism B, without need for excessive length of conveyor belt 6 they are disposed on opposite sides of the conveyor; accordingly, the operators at the assembly and transfer stations respectively are seated on opposite sides of the conveyor belt 6.

In the system shown in Figs. 16 and 17, the sheet-applying mechanism M1, the adhesive applying mechanism G1, and the blank bending mechanism B, may all be the same as disclosed in Figs. 7-9 rearranged however as now described for use with a single operator. As illustrated in Figs. 16 and 17, the operator is seated at 7 opposite the wrapper-applying mechanism M1 with the conveyor belt 6A of the adhesive-applying mechanism extending between her and the wrapper-applying mechanism. The blank bending and delivering mechanism B is so disposed that the discharge end of its conveyor 10 is adjacent the discharge end of the wrapper conveyor 6A; the conveyors, as indicated, move in opposite directions.

The conveyors 10 and 6A are so timed that in each cycle of the system a box blank and a wrapper are fed toward the operator and come to rest at different predetermined positions each within easy reach of her. Each of the box blanks arrives in predetermined orientation with respect to the orientation of the wrappers so avoiding confusion or need for close attention by the operator.

operator; preferably the box blanks on conveyor 6 are substantially at right angles to the position each is to assume in formation of an assembly A so that the operator, by the natural swinging movement necessary to move the blanks to position in front of her at the same time turns the blank into position of register with the wrapper.

The operator, after forming the assembly, lifts it onto the form block 12A of the wrapping machine M1 and momentarily holds it there as previously mentioned. The mechanisms M1, B, G1 are so timed that the dwell of the conveyor 6A between successive steps is sufficiently long to allow accurate register of the box blanks on the wrappers. Notwithstanding the operator performs both of the acts of forming the assembly and transferring it to the form block, the fatigue is less, even when the system is operated at higher rate of wrapped boxes per minute than in prior semi-automatic systems in which the operator in each cycle had to separate a box blank from a stack thereof with attendant difficulties above mentioned.

As evident from Fig. 18, the operator by manipulating the control handle 8 may interrupt the supply of wrappers and tabs to the conveyor 6A yet allow continued step-by-step movement thereof for feed to her of the wrappers already on it. At the beginning of a run she may, by depressing a treadle 35, initiate operation solely of the sheet-coating mechanism G1 until the first of the coated wrappers reaches her at the assembly station; by operation of the knob 76; or the treadle 16A, she may, independently of the operation of the wrapping mechanism M1, provide for feed to her of box blanks. In the normal operation of the system, the operator holds the treadle 102 depressed for continuous repetition of the cycle of the sheet-applying mechanism M1 and in each cycle thereof, the cams 38 and 71 trip the clutches of the adhesive-applying mechanism G1 and the blank bending mechanism B to provide for feed to the operator of another wrapper and another box blank.

The system shown in Figs. 19 and 20, is similar to that of Figs. 16 and 17 except that the wrapper conveyor, because of desired use of the system for making large boxes, is too wide to be interposed between the operator and mechanism M1. In each cycle, the operator first removes a wrapper from conveyor 6, places it upon the registering table 193, and then removes a box blank BB from conveyor 10 and registers it upon the wrapper. The assembly so formed is then placed by the operator upon the form block 12A of the wrapping machine.

The delivery of the box blanks BB to a predetermined position adjacent the operator individually and in predetermined orientation, so reduces the demand upon the operator's attention that it is possible, as compared with the case in which the box blanks must be removed individually by the operator from a stack, to obtain neater boxes and higher rate of production thereof with less fatigue.

The controls located adjacent the operator for her supervision of the operation of the several mechanisms G1, M1 and B are the same as disclosed in Fig. 18 and described in connection therewith.

It is characteristic of all of the modifications described that the wrappers and box blanks are fed individually toward an operator and that each wrapper and box blank comes to rest in predetermined orientation with respect to the

other, to facilitate transfer by the operator of the box blank into registered adhesive engagement with the wrapper. It is characteristic of all of the systems disclosed that controls for the blank bending and delivering mechanism, the wrapper-applying mechanism, and the adhesive-applying and sheet-feeding mechanism, are all disposed at the assembly station for control thereby by the operator of the several mechanisms.

It shall be understood the term "unstayed box blank" as herein used defines a box blank whose walls are not held erect or in box-forming position by stays or tabs.

What I claim is:

1. In a semi-automatic box-making system in which an operator at a station manually registers box structures and adhesively coated wrappers, a conveyor for transporting the wrappers in succession to said station, means for delivering coated wrappers to said conveyor, means for delivering box blanks individually adjacent said station, one for each wrapper, and control means at said station actuatable by said operator for interrupting delivery of wrappers to said conveyor by said first-named means during continuing operation of the conveyor, for controlling the operation of the conveyor independently of the control of said first-named means, and for controlling operation of said blank-delivering means independently of control of said conveyor and of said first-named means.

2. In a semi-automatic box-making system in which an operator at an assembly station manually registers box structures with adhesively coated wrappers, mechanism operative in each of its cycles to deliver a box blank to said station, a conveyor for transporting wrappers in succession to said station, adhesive-applying mechanism operative in each of its cycles to advance said conveyor and including means for feeding a wrapper to the conveyor, means automatically controlling said mechanisms to provide said operator with wrappers and box-blanks, one for each wrapper, and control means actuatable at said station by the operator at will to initiate the cycle of each of said mechanisms independently of said automatic control means, and to disable said wrapper-feeding means during continued operation of said conveyor.

3. In a semi-automatic box-making system in which an operator at an assembly station manually registers box structures with adhesively coated wrappers, a conveyor for transporting the wrappers in succession to said station, means for delivering coated wrappers to said conveyor, means for delivering box blanks individually to said station, one for each wrapper, and control means actuatable at said station by said operator for interrupting delivery of wrappers to said conveyor by said first-named means during continued operation of the conveyor, for controlling the operation of the conveyor independently of control of said first-named means, for controlling operation of said blank-delivering means independently of control of said conveyor and of said first-named means, and to control initiation and interruption of operation of said automatic control means.

4. In a semi-automatic box-making system in which an operator at an assembly station manually registers box structures with adhesively coated wrappers to form assemblies converted by a wrapping machine into wrapped boxes, a mechanism operative in each of its cycles to deliver a box blank to said station, a conveyor for trans-

porting wrappers in succession to said station, adhesive-applying mechanism operative in each of its cycles to advance said conveyor and including means for feeding a wrapper thereto, automatic control means included in said wrapping machine for individually controlling said mechanisms, and control means actuatable at said station by the operator to control initiation and interruption of operation of said wrapping machine, to initiate the cycle of each of said mechanisms independently of said automatic control means, and to disable said wrapper-feeding means during continued operation of said conveyor.

5. In a semi-automatic box-making system in which an operator at an assembly station manually registers box structures with adhesively coated wrappers to form assemblies converted by a wrapping machine into wrapped boxes, a mechanism operative in each of its cycles to deliver a box-blank to said station, a conveyor for transporting wrappers to said station and for transporting the assemblies from said station to a transfer station adjacent said wrapping machine, adhesive-applying mechanism operative in each of its cycles to advance said conveyor and including means for feeding a wrapper thereto, automatic control means included in said wrapping machine for individually controlling said mechanisms, and control means actuatable at said station by the operator to control initiation and interruption of operation of said wrapping machine, to initiate the cycle of each of said mechanisms independently of said automatic control means, and to disable said wrapper-feeding means during continued operation of said conveyor.

6. In a semi-automatic box-making system in which an operator at an assembly station forms, from box blanks and adhesively-coated wrappers, assemblies placed by another operator at a transfer station into a wrapping machine, a conveyor for transporting wrappers to said station and for transporting the assemblies from said station to the second-named operator, mechanism operative in each of its cycles to deliver a box blank to said station, adhesive applying mechanism operative in each of its cycles to advance said conveyor and including means for feeding a wrapper thereto, automatic control means included in said wrapping machine for individually controlling said mechanisms, and control means actuatable by at least one or the other of said operators to control, from at least one of said stations initiation and interruption and interruption of operation of said wrapping machine, to initiate the cycle of each of said mechanisms independently of said automatic control means, and to disable said wrapper-feeding means during continued operation of said conveyor.

7. A semi-automatic system for producing assemblies of unstayed box blanks and wrappers comprising an intermittently operating conveyor delivering coated tabbed wrappers individually at definitely timed intervals to an operator's assembling station, a second conveyor delivering unstayed box blanks individually, one for each wrapper, at definitely timed intervals, corresponding with aforesaid intervals, each to rest at a predetermined position within operator's reach of said assembling station and in predetermined orientation, at said predetermined position of rest, with respect to the orientation of a wrapper on said first-named conveyor at rest at said assembling station for manual transfer of each

unstayed box blank from its said predetermined position of rest to said assembling station for manual register with the wrapper at rest thereat, and selectively operable means at the operator's assembling station for simultaneously enabling or disabling said conveyors and for individually enabling or disabling said conveyors.

8. A semi-automatic system for producing assemblies of unstayed box blanks and wrappers comprising an automatic mechanism, including a conveyor, for delivering coated tabbed wrappers individually at definitely timed intervals to an operator's assembling station, an automatic mechanism for delivering unstayed box blanks individually at definitely timed intervals, corresponding with aforesaid intervals, each to rest at a predetermined position within operator's reach of said assembling station and in predetermined orientation at said predetermined position with respect to the orientation of a wrapper when at rest on said conveyor at said assembling station, for manual transfer of each unstayed box blank from its said predetermined position of rest into register with said wrapper at rest on said conveyor, and selectively operable means at the operator's assembling station for simultaneously enabling or disabling said automatic mechanisms and for individually enabling or disabling said automatic mechanisms.

9. A semi-automatic system for production of wrapped stayed boxes from assemblies of unstayed box blanks and coated tabbed wrappers, comprising an automatic mechanism, including a conveyor, for delivering coated tabbed wrappers individually at definitely timed intervals to an operator's assembling station, an automatic mechanism for converting assemblies of unstayed box blanks and wrappers into stayed wrapped boxes, an automatic mechanism for delivering unstayed box blanks individually at definitely timed intervals, corresponding with aforesaid intervals, each to rest at a predetermined position within operator's reach of said station and in predetermined orientation at said predetermined position with respect to the orientation of a wrapper when at rest on said conveyor at said assembling station, for manual transfer of each unstayed box blank from its said predetermined position at rest into register with said wrapper at rest on said conveyor, the conveyor which delivers coated tabbed wrappers individually to said operator's assembling station delivering the assemblies produced at said assembling station in succession to a second operator's station, within operator's reach of said assembly-converting mechanism, for manual transfer of the assemblies to said assembly-converting mechanism, and selectively operable means at said operator's assembling station and at said second operator's station for simultaneously enabling and disabling said automatic tabbed wrapper delivering mechanism and said automatic unstayed box-blank delivering mechanism and for individually enabling or disabling said automatic tabbed wrapper delivering mechanism and said automatic unstayed box blank delivering mechanism.

10. A semi-automatic system for production of wrapped stayed boxes from assemblies of unstayed box blanks and coated tabbed wrappers, comprising an automatic mechanism, including a conveyor, for delivering coated tabbed wrappers individually at definitely timed intervals to an operator's assembling station, an automatic mechanism for converting assemblies of unstayed box blanks and wrappers into stayed wrapped boxes, an automatic mechanism for delivering unstayed box blanks individually at definitely timed intervals, corresponding with aforesaid intervals, each to rest at a predetermined position within operator's reach of said station and in predetermined orientation at said predetermined position with respect to the orientation of a wrapper when at rest on said conveyor at said assembling station for manual transfer of each unstayed box blank from its said predetermined position at rest into register with said wrapper at rest on said conveyor, means for delivering the assemblies produced at said assembling station in succession to a second operator's station, within operator's reach of said assembly-converting mechanism, for manual transfer of the assemblies to said assembly-converting mechanism, and means actuatable by either of said operators for controlling operation of said automatic mechanisms.
11. A method of producing assemblies of unstayed box blanks and coated tabbed wrappers comprising delivering the wrappers individually at definitely timed intervals to an operator's assembling station, delivering unstayed box blanks individually, one for each wrapper, to rest at a predetermined position, within operator's reach of said assembling station, and in predetermined orientation at said predetermined position of rest with respect to a wrapper at rest at said assembling station, and manually transferring each unstayed box blank from its said predetermined position of rest to and registering it with the wrapper at rest at said assembling station.
12. A method of producing wrapped stayed boxes from assemblies of unstayed box blanks and coated tabbed wrappers comprising delivering the wrappers individually at definitely timed intervals to an operator's assembling station, delivering unstayed box blanks individually, one for each wrapper, to rest at a predetermined position, within operator's reach of said assembling station, and in predetermined orientation at said predetermined position of rest with respect to the orientation of a wrapper at rest at said assembling station, manually transferring each unstayed box blank from its said predetermined position of rest to and registering it with the wrapper at rest at said assembling station, delivering the assemblies so produced in succession, at intervals corresponding with aforesaid intervals, to an operator's assembly-feeding station, and there manually feeding the assemblies in succession and converting them into stayed wrapped boxes.
